US00D946583S

(12) **United States Design Patent** (10) **Patent No.:** **US D946,583 S**
Hines et al. (45) **Date of Patent:** **** Mar. 22, 2022**

(54) **DISPLAY SCREEN WITH GRAPHICAL USER INTERFACE**

(71) Applicant: **Dose Health, LLC**, New Brighton, MN (US)

(72) Inventors: **Paul Hines**, Minneapolis, MN (US); **Hayden Schoen**, Tacoma, WA (US)

(73) Assignee: **Dose Health, LLC**, New Brighton, MN (US)

(**) Term: **15 Years**

(21) Appl. No.: **29/652,911**

(22) Filed: **Jan. 7, 2021**

Related U.S. Application Data

(62) Division of application No. 29/653,236, filed on Jun. 13, 2018, now Pat. No. Des. 910,029.

(57) **CLAIM**

The ornamental design for a display screen with graphical user interface, as shown and described.

DESCRIPTION

The FIGURE is a front view of a display screen with graphical interface showing the new design.

The broken lines showing a medication dispenser illustrate environmental subject matter, whereas the broken lines showing a display screen and elements of the graphical user interface illustrate portions of the article. None of the broken lines form part of the claimed design.

1 Claim, 1 Drawing Sheet
